UNITED STATES PATENT OFFICE

90,942

DESIGN FOR A PORCH LIGHT

Thomas Dominick, Sacramento, Calif.

Application August 14, 1933. Serial No. 49,022

Term of patent 14 years

To all whom it may concern:

Be it known that I, THOMAS DOMINICK, a citizen of the United States, residing at Sacramento, in the county of Sacramento and State of California, have invented a new, original, and ornamental Design for a Porch Light, of which the following is a specification, reference being had to the accompanying drawings, forming part thereof.

I claim:—

The ornamental design for a porch light as shown.

THOMAS DOMINICK.
